(57) **CLAIM**

The ornamental design for a candy jar, as shown and described.

DESCRIPTION

FIG. 1 is a perspective view of the candy jar showing our new design;

FIG. 2 is a front elevation view thereof;

FIG. 3 is a top plan view thereof;

FIG. 4 is a right side elevation view thereof;

FIG. 5 is a left side elevation view thereof;

FIG. 6 is a bottom plan view thereof;

FIG. 7 is rear elevation view thereof; and,

FIG. 8 is a perspective view of an alternate embodiment thereof.

The broken lines shown in the drawings illustrate environment and forms no part of the claimed design.
